OVERHEAD DOOR

Eugene H. Sawyer, West Bend, Wis., assignor to Phenix
Manufacturing Company, Inc., Milwaukee, Wis., a corporation of Wisconsin

Filed Nov. 18, 1963, Ser. No. 77,461

Term of patent 14 years

(Cl. D13—1)

Fig. 1

FIG. 2

FIG. 4

FIG. 1 is a front elevation view of an overhead door embodying the design of this invention; and FIGS. 2, 3 and 4 are sectional views taken along lines 2—2, 3—3 and 4—4, respectively, of FIG. 1.

I claim:

The ornamental design for an overhead door, substantially as shown.
